UNITED STATES PATENT OFFICE.

WALTER STAFFORD AND ROBERT C. HOLT, OF LITTLE FALLS, NEW YORK.

KNITTING MACHINE.

Application filed December 30, 1925. Serial No. 78,347.

This invention relates to knitting machines.

The purpose of our invention is to provide a knitting machine which is adapted to knit patterns or designs in the knitted fabric and to have the knitting machine of such form, construction and arrangement of its parts that a great variety of designs or patterns may be knitted by appropriate adjustment 10 and arrangement of the parts of the device which adjustments can be readily made on the machine.

A further purpose is to provide in a knitting machine designer wheels having a plurality of places or slots in some of which are carried needle selectors with the designer wheel adapted to be rotated bodily past the stationary needles and with the dial plate of said designer wheel in turn rotating 20 on its own center so as to successively bring its several needle selectors into engagement with the corresponding needles of the knitting machine in such manner that where a needle selector is present opposite a needle such needle is projected into feeding position while the needles opposite to which no needle selectors are placed are not projected at said feed and so do not receive any yarn 25 at that feed but retain their old stitches.

30 A further purpose is to provide a knitting machine of the class described where the design wheels are of such construction and co-operation with the needles of the knitting machine that more than two different colored 35 yarns may be used in a design by the employment of design wheels of a number corresponding to the colors of yarn desired to be used. Our machine is particularly adapted to be used upon machines making ribbed 40 fabric; that is machines where dial needles and cylinder needles are used; in such a machine our device may be used in direct co-operation with the dial needles. In the 45 specification and drawings herein we have described and illustrated our invention as embodied in design wheels co-operating directly with the dial needles as this arrangement is perhaps somewhat simpler and is more convenient and desirable as a machine 50 and makes a better fabric with lower grades of yarn.

Fig. 1 is a vertical sectional view through part of a knitting machine embodying our invention on line 1—1 of Fig. 2.

55 Fig. 2 is a top or plan view of part of said machine.

Figs. 3 and 4 are side and top views of the needle selector on an enlarged scale.

Fig. 5 is a side view of a needle selector and a needle in operative position. 60

Figs. 6 and 7 are top views of said selector and needle in angular and straight engagement representing initial and final angles at which said parts operate.

Fig. 8 is a side view of a dial needle. 65

Upon the stationary cylinder 10 are provided the usual outwardly opening vertical slots in which are mounted the cylinder needles 11 for vertical reciprocation in the usual way by cams 12 projecting inwardly 70 from the revolving cam carrier 13.

Within the cylinder 10 is mounted the stationary horizontal dial 14 having the usual upwardly opening and radially arranged slots 15 in which are slidably mounted the dial needles 16 having the usual butts 17 extending above the upper face of the dial. The dial 14 is supported by and attached to a large narrow gear wheel 18 having inwardly projecting teeth 19 and this wheel is in turn attached to and stationarily supported by the large stationary disk 20 conveniently formed with an integral hub 21 supported by the usual central upright 22. 85

Above the dial 14 there is provided a rotating cap plate 23 which has a plurality of large spaced openings 24 therein intermediate the hub portion 25 and the rim portion 26 leaving a similar number of spider like spokes or arms 27 connecting the hub and the rim. This cap plate carries the usual downwardly facing retracting cams 28 and guard cams 29 operating against butts 17 of the dial needle 16 in the usual way. 90 In this cap plate, however, there are located no projecting or "riser" cams for projecting the needles outwardly into operative position, but such projecting of the needles outwardly into operative position is accomplished by needle selectors 30 mounted in designer wheels generally denoted by the numeral 31. 95

One of these designer wheels 31 is located in each of the large openings 24 of the rotating cap plate 23 and is mounted to rotate bodily with said cap plate but to be separately rotated on its own axis while so rotating bodily with the said cap plate. Extending over each opening 24 from two adjacent arms 27 of the cap plate there is provided a bridge piece 32 rigidly fastened 100 110

to the arms as by bolts 33. Dependingly secured to this bridge piece 32 there is provided the stud shaft 34 as by nuts 35 at the top of the bridge piece engaging the upper 5 end of said shaft above the bridge piece while the shoulder 36 formed by the enlarged diameter of the said shaft immediately below the bridge bears against said lower side of the bridge piece. An integral head or 10 enlargement 37 on the lower end of the stud shaft 34 preferably with the aid of an intervening washer 38 supports the designer wheel 31 on said stud shaft.

This designer wheel consists of a secondary 15 or designer dial 39 and a pinion 40 normally fastened together and traveling together but having means for accurate adjustment between said two parts as will be hereinafter mentioned. This designer pinion 40 is of 20 such size and the said designer wheel is so mounted that the teeth of said pinion on its side towards the cylinder mesh with the teeth 19 of the large gear wheel 18 which as already mentioned is stationarily mounted 25 upon the disk 20. It will be seen, therefore, that rotation of the cap plate 23 carrying bodily therewith the several designer wheels 31 will cause said designer wheels to rotate on the stud shafts 34 through the pinion 40 30 having engagement with the gear wheel 18.

In the secondary or designer dial 39 there are provided radially arranged upwardly facing slots extending in from the periphery of said dial and adapted to slidably receive 35 therein the needle selectors 30 with the butts 41 of said needle selectors projecting above the upper face of said dial 39.

Mounted directly above the outer or needle selector-carrying part of the secondary dial 40 39 there is mounted the designer cap plate 42. Said cap plate is fastened to the bridge piece 32 as by screws 43 extending down from said bridge piece into the said cap plate with said screws also passing through spacing rings 44 interposed between said cap plate and said bridge piece. In the bottom 45 of this cap plate 42 there is provided for most of the circumference of said cap plate a downwardly opening annular groove 45 in 50 which travel the upstanding butts 41 of the needle selectors 30.

Said groove 45 may be made directly in the designer cap plate 42 but preferably is made in a separate cam plate 47 attached 55 to said cap plate and so mechanically forming a part thereof. On the portion of the cap plate towards the needle dial there are provided in the cam plate 47 a projecting cam 48 for projecting the needle selectors farther out upon the designer dial and a re- 60 tracting cam 49 for withdrawing said selectors back to the annular groove 45.

It will be understood that the slots in the designer dials 39 are spaced apart the same 65 distance as the slots 15 in the main horizontal

dial 14 so that the needle selectors 30 in the slots beneath the projecting cam 48 and for a short distance before that is reached by the adjacent slots of the selector dial are sufficiently in alignment with the oppositely 70 placed needles in the main dial 14 then approaching a given feeding position of the knitting machine to make the outer ends of the needle selectors engage the upstanding butts 17 on the dial needles and push said 75 needles out to operative position as the respective needle selectors are projected farther outward on the designer dial incident to the upstanding butts upon the selectors having to follow the path of said projecting cam 80 48 of the selector cap. The needles so projected to feeding position at any feed receive the thread provided for that feed and the needles are thereafter retracted by the retractor cam 28 upon the main cap plate 23 85 of the machine while the needle selectors have been promptly and previously retracted by the retracting cam 49 on the designer cap plate.

It will be understood that these designer 90 wheels must be arranged in sets, usually two or three and perhaps four designer wheels being used to effect the knitting of the desired pattern. If yarns of only two different colors are being used only two designer 95 wheels need to be used. In such a two-wheel set selectors will be placed in certain of the slots of the first designer wheel and omitted from the other slots and this will cause the corresponding needles at this first 100 feed to be projected into feeding position and knit a stitch on each of the needles so projected. The next designer wheel will have needle selectors put into its slots which correspond to the slots in the first designer 105 wheel where no needle selectors were placed so that at this second feed the second designer wheel will project into feeding position only such needles as were not projected into feeding position at the first feed. 110 Where it is desired to have a design using three colors or shades of color three designer wheels will be used at three successive feeds and the needle selectors will be placed in the respective designer wheels so as to bring 115 all of the dial needles into operation once only during said set of three feeds. The design stitches will obviously be longer than the stitches knitted by the cylinder needles.

For instance, when two designer wheels are 120 used for knitting a design the design stitches knitted by the dial needles will be twice as long as the regular backing stitches knitted by the cylinder needles since the cylinder needles knit at each feed and the dial needles knit once at each two feeds. Obviously when three designer wheels are used the design stitches will be three times as long as the stitches knitted by the cylinder needles. And as the stitches cannot be kept 130

indefinitely upon the dial needles it is necessary that all of the dial needles be brought into operation at each complete set of designer wheels. It will be understood that at any feed where there is no needle selector opposite a given dial needle that needle will simply retain its previous stitch.

As many sets of designer wheels may be used on a knitting machine as there is room to receive. On an ordinary four feed machine there may be two sets of two designer wheels each or only one four-wheel set. On a six feed machine there may be two sets of three wheel sets or three sets of two wheel sets.

Each designer dial 39 and its pinion 40 therebelow are normally rigidly fastened together as by headed screws 50 having their heads above the designer dial 39 and having their shanks project downwardly through elongated slots 51 in the designer dial with the lower end of said screws threaded into the pinion 40. This arrangement allows a slight rotative adjustment to be made between the designer dial and its pinion by first loosening said screws 50 and then adjusting the horizontally arranged screw-threaded rod 52 mounted upon the top of the designer dial. This screw-threaded rod is rotatively mounted intermediate its ends in the top of a stud 53 upstanding from the pinion through a suitable slot in the designer dial, said rod being held from longitudinal play in said stud as is usual in devices of this character. The opposite ends of said rod are screw-threaded into the upper ends of a pair of short ears 54 and 55 upstanding from the designer dial. When the desired adjustment or "chiming" of the parts has been accomplished the screws 50 will be again tightened to hold the designer dial and its pinion rigidly together.

What we claim as new and desire to secure by Letters Patent is:

1. In a circular independent-needle knitting machine the combination of a stationary needle dial, needles radially carried thereby with butts projecting from said dial, a plurality of feeds therefor, a main rotating member having cams to withdraw said needles from operative position, a stationary gear wheel, a plurality of complementary designer wheels bodily carried by said main rotating cam member each designer wheel having a dial within the circle of the needle dial and provided with radial slots spaced similarly to the needles, one edge of the designer dial being adjacent the needle dial, a pinion engaging the teeth of said gear wheel and adapted to rotate said designer dial and removable needle selectors slidably mounted in certain of the slots of said designer dial and at the outer part of the designer dial substantially aligned with the dial needles and adapted to engage the butts

of certain of the needles and move said needles to operative position and a cap plate for each designer wheel mounted on said main rotating cam member and located opposite said needle selectors and having cams for projecting the needle selectors into engagement with the needles and to withdraw the selectors therefrom.

2. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

3. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

4. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

5. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

6. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

7. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

8. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

9. In a circular independent-needle knitting machine the combination of a needle dial, needles radially carried thereby with butts projecting from said dial, a plurality of feeds therefor, a main rotating member having cams to withdraw said needles from operative position, means to effect relative rotative movement between said dial and said main cam member, a plurality of complementary designer wheels bodily carried by said main rotating cam member each designer wheel having a dial within the circle of the needle dial with radial slots and with one edge adjacent the needle dial and removable needle selectors slidably mounted in said designer dial and at the outer part of the designer dial substantially aligned with the dial needles and adapted to engage the butts of certain of the needles and move said needles to operative position and a cap plate for each designer wheel mounted on said main cam member and located opposite said needle selectors and having cams for projecting the needle selectors into engagement with the needles and to withdraw the selectors therefrom.

4. In a circular independent-needle knitting machine, the combination of a stationary dial, needles slidingly and radially mounted therein and provided with projecting butts, a plurality of feeds therefor, a main rotating cap having cams to withdraw said needles from operative position, a stationary gear wheel below the needle dial near its outer edge, a plurality of complementary designer wheels bodily carried within the circle of the needle dial by said main rotating cap plate, each designer wheel having a dial within the circle of the needle dial with radial slots and with one edge adjacent the edge of the needle dial and a pinion below the designer dial and engaging the teeth of said gear wheel and adapted to rotate said designer dial and needle selectors slidingly and radially mounted in the slots of the designer dial and adapted by outward radial movement in a line approximating the radial travel of the needles to engage the butts of certain of the needles and move said needles to operative position and a cap plate for each designer wheel mounted on said main rotating cap plate and located opposite said needle selectors and having cams for projecting the needle selectors into engagement with the needles and to withdraw the selectors therefrom.
5. In a circular independent-needle knitting machine, the combination of a plurality of feeds, a stationary needle cylinder, needles slidingly mounted therein and provided with projecting butts, a main rotating cap having cams to withdraw said needles from operative position, a stationary needle dial, needles slidingly and radially mounted therein and provided with projecting butts, a main rotating cap having cams to withdraw said needles to and from operative position, a plurality of complementary designer wheels bodily carried within the circle of the needle dial by said main rotating cap plate, each designer wheel having a dial with radially arranged slots spaced corresponding to the dial needles and with one edge adjacent the edge of the needle dial and removable needle selectors slidingly and radially mounted in said designer dial and adapted by outward radial movement in a line approximating the radial travel of the needles to engage the butts of certain of the needles and move said needles to operative position and a cap plate for each designer wheel mounted on said main rotating cap plate and located opposite said needle selectors and having cams for projecting the needle selectors into engagement with the needles and to withdraw the selectors therefrom.
6. In a circular independent-needle machine the combination of a plurality of feeds, a stationary needle cylinder, needles slidingly mounted therein and provided with projecting butts, a main rotating cap having cams to withdraw said needles to and from operative position, a stationary needle dial, needles slidingly and radially mounted therein and provided with projecting butts, a main rotating cap having cams to withdraw said needles to and from operative position, a stationary gear wheel in a plane parallel with the needle dial, a plurality of complementary designer wheels bodily carried within the circle of the needle dial by said main rotating cap plate, each designer wheel having a dial with radially arranged slots spaced corresponding to the needles and with one edge adjacent the edge of the needle dial and a pinion engaging the teeth of said gear wheel and adapted to rotate said designer dial and needle selectors slidingly and radially mounted in the designer dial and adapted by outward radial movement in a line approximating the radial travel of the needles to engage the butts of certain of the needles and move said needles to operative position and a cap plate for each designer wheel mounted on said main rotating cap plate and located opposite said needle selectors and having cams for projecting the needle selectors into engagement with the needles and to withdraw the selectors therefrom.
7. In a circular independent-needle knitting machine the combination of a needle dial, needles radially carried thereby with butts projecting from said dial, a plurality of feeds therefor, a main cam member having cams to withdraw said needles from operative position, means to effect relative rotative movement between said dial and said main cam member, a plurality of complementary designer wheels mounted on said main cam member, each designer wheel having a dial within the circle of the needle dial, with one edge adjacent the needle dial and removable needle selectors slidingly and radially mounted in said designer dial and adapted by outward radial movement in a line approximating the radial travel of the needles to engage the butts of certain of the needles and move said needles to operative position and a cap plate for each designer wheel mounted on said main cam member and located opposite said needle selectors and having cams for projecting the needle selectors into engagement with the needles and withdraw the selectors therefrom and means to rotate said designer wheel dials in unison with the rotating member of said needle dial and main cam member pair.
- In witness whereof we have affixed our signatures, this 30th day of November 1925.
